United States Patent

Des. 240,035
Patented May 25, 1976

240,035

MULTI-PURPOSE KNIFE

George J. Ruth, 6934 Calhoun St.,
Dearborn, Mich. 48126

Filed July 26, 1974, Ser. No. 492,285

Term of patent 14 years

Int. Cl. D7—03; D8—03

U.S. Cl. D22—31

FIG. 1 is a side elevation view of a multi-purpose knife embodying my new design.

FIG. 2 is a top plan view thereof, taken on plane 2—2 in FIG. 1.

FIG. 3 is a bottom plan view thereof, taken on plane 3—3 in FIG. 1.

FIG. 4 is a side elevation view thereof, taken on plane 4—4 in FIG. 2.

FIG. 5 is an end view thereof, taken on plane 5—5 in FIG. 2.

I claim:

The ornamental design for a multi-purpose knife, as shown.
